US00D949832S

(12) **United States Design Patent** (10) **Patent No.:** **US D949,832 S**
Zhou (45) **Date of Patent:** **** Apr. 26, 2022**

(54) **WIRELESS EARBUDS WITH CHARGING CASE**

(71) Applicant: **HANK ELECTRONICS CO., LTD,**
Shenzhen (CN)

(72) Inventor: **Yuchun Zhou**, Shenzhen (CN)

(73) Assignee: **HANK ELECTRONICS CO., LTD,**
Shenzhen (CN)

(**) Term: **15 Years**

(21) Appl. No.: **29/757,065**

(22) Filed: **Nov. 3, 2020**

(51) **LOC (13) Cl.** **14-01**

(52) **U.S. Cl.**

USPC **D14/223**

(57) **CLAIM**

The ornamental design for wireless earbuds with charging case, as shown and described.

DESCRIPTION

FIG. 1 is a perspective view of wireless earbuds of wireless earbuds with charging case, shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof;

FIG. 9 is a perspective view of a charging case of the wireless earbuds with charging case, shown separately for ease of illustration and in an open configuration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of the wireless earbuds with charging case, shown in use with the wireless earbuds received in the charging case; and,

FIG. 18 is a perspective view of the charging case of the wireless earbuds with charging case, shown separately for ease of illustration and in a closed configuration.

The broken lines in the drawings depict portions of the wireless earbuds with charging case that form no part of the claimed design.

1 Claim, 18 Drawing Sheets
